Atkins & Atkins,
ATTORNEYS.

UNITED STATES PATENT OFFICE.

ELIAS BERTON ROSE, OF PORTLAND, OREGON.

AIR-GAUGED FILLER VENT.

Application filed January 10, 1921. Serial No. 436,284.

To all whom it may concern:

Be it known that I, ELIAS BERTON ROSE, a citizen of the United States of America, and a resident of the city of Portland, in the county of Multnomah, in the State of Oregon, have invented certain new and useful Improvements in Air-Gauged Filler Vents, of which the following is a specification, reference being had to the accompanying drawing.

My invention relates to filler-vents primarily adapted for supplying air to pneumatic tires, for gauging the pressure of the confined volume of air so supplied, and for utilizing at will the air supply for other and independent purposes.

My present invention is in the nature of an improvement upon that set forth in my application for United States Letters Patent, No. 416,463, filed October 12, 1920, in so far as both inventions have certain features in common.

The principal object of my invention is to simplify the principle, the construction, and the mode of operation of my device. Other objects will appear to one skilled in the art upon perusal of the following specification, wherein what constitutes my invention is described in detail and is succinctly set forth in the appended claims.

In the accompanying drawing,

Figure I is a diametrical vertical section, partially in elevation, of my present invention in preferred form of embodiment, the section being taken to include the gauge and air pipe connection, and the parts being shown as if actuated by tire pressure.

Figure II is a view similar to Figure I showing the air valve in position as if actuated to admit passage of air to a tire.

Figure III shows a part of the subject matter of Figure I, and attached thereto a longitudinal section of a nozzle attachment.

Figure IV is a bottom plan view of a portion of the subject matter of Figure I.

Referring to the numerals on the drawing, 1 indicates the barrel of my filler-vent that is provided on one side, with an internally threaded gauge socket 2 and an elongated pipe nipple 3. The longitudinal axes of the members 2 and 3 are parallel to each other and both are radial to the longitudinal axis of the barrel 1.

The longitudinal bore of the barrel 1 is preferably composed of sections 4 and 5 of

different diameters, the former being the one of smaller diameter.

The section 4 is disposed so as to make direct communication with the socket 2 through a duct 6 formed in the wall of the barrel 1.

The outer end of the section 4 is snugly fitted with a plunger 7 into the inner end of which is threaded a tang 8 upon the end of a stem 9 of smaller diameter than that of the bore section 4 which surrounds it on two sides. Between the opposing ends of the plunger 7 and the stem 9 is secured an intermediate laterally projecting packing ring 10 which, through reciprocation of the plunger 7, serves to permit or to exclude communication between the end of the duct 6 and the interior of the bore section 4.

Upon its end opposite the plunger 7 the stem 9 terminates in a valve actuating head 15 which is preferably provided with oppositely disposed conical zones 16 and 17 and which fits loosely within the bore section 5. An inclined passage way 18 through the head 15 penetrates the two walls 16 and 17. The two bore sections 4 and 5 are separated at 19 by a preferably inclined annular wall, the angle of whose inclination corresponds substantially to that of the zone 16.

The shape of the zone 16 is only preferred for convenience of assembling the parts of the device, but the zone 17 performs, by reason of its shape, an important function, namely, that of actuating an air control valve 20, whose nose 21 projects radially into the bore section 5 in the path of movement of the actuating valve head 15, and which is snubbed back with valve opening effect upon each reciprocation of the plunger 7 and the stem 9 which is, in effect, a continuation of the plunger.

The valve actuating head 15 with its attached plunger 7 is preferably spring supported with reference to the barrel 1, or, in other words, the zone 16 is yieldingly urged against the wall 19. That effect may be conveniently arrived at through the employment of a coiled spring 25 seated at one end against the valve actuating head 15 and surrounding a projection 26 extending therefrom coaxially with the stem 9, the spring 25 being seated at its opposite end against the top of a disk 27 by which the end of the bore section 5 is closed, except for the presence therein of ducts 28 on opposite

sides of a stud 29 upon the disk, which the terminal coils of said spring encircle.

It is convenient, at this point, to specify that construction and arrangement for the accommodation of the disk 27, which I prefer. Accordingly, it is stated that 30 indicates a cylindrical cavity formed in the end of the barrel 1, coaxially with and of greater diameter than the bore thereof. The wall of 10 said cavity being internally threaded, the disk 27, being seated in the bottom of the cavity, is confined in place by a threaded ring 31 screwed into the cavity against an intermediate gasket 32. A stud 33 projects 15 through the gasket 32 in the opposite direction from the stud 29.

I prefer to provide threads on the inside of the ring 31 to receive a nozzle attachment 36, which, being provided with an inclined 20 branch nipple 37, may be connected by a pipe to a source of liquid supply and made to operate, by suction caused by discharge of air through it, to draw in liquid from 25 said source of supply and to discharge it in a spray from the end of the nozzle 36.

The effect last described may be utilized to advantage about a garage and is made available in my filler-vent simply by providing it with the means of connection for the 30 attachment 36, as specified.

Reverting, now, to the description of the air control valve 20, it remains to be specified that said valve is preferably provided with a coaxial stem 38 that terminates, at 35 one end, in the nose 21 already specified, and whose other end is guided in its reciprocal movement through an aperture in a collar 40, threaded into the bore of the nipple 3 and screwing into stop engagement with a shoulder 41. A coiled spring disposed about 40 the stem 38 between the reverse side of the valve 20 and the collar 40, serves yieldingly to set the said valve upon its seat 42. The part of the stem 38 between its nose 21 and 45 the valve 20 reciprocates loosely in a passage 43 between the bores of the barrel 1 and the nipple 3, respectively. The complementary contours of the valve 20 and its seat 42 serve to hold the nose 21 in place, 50 while the displacement of the valve through engagement of the zone 17 and the nose 21 of the valve stem 38 is so slight as to necessitate no other provision for its guidance than the conicity of the valve 20 and its 55 seat, respectively.

Into the open end of the socket 2 is screwed, with stiffening effect, a gauge case 45 within which, as upon a spacing collar 46, is confined a gauge shell 47. A cylindrical gauge 48 works reciprocally within the space between the gauge case 45 and the gauge shell 47, and is provided with a head 50 which is laterally extended so as to serve as a protective cap to the gauge case when 60 closed against it.

To the inside of the head 50 is secured at one end a rod 51 that is provided at its other end with a piston head 52. The gauge shell 47 is inwardly flanged at its outer end, as indicated at 53, to afford a seat for one end 70 of a coiled spring 54 that is seated at its other end against the piston head 52, with the effect of yieldingly confining the gauge 48 within its shell by a force measured by the power of the spring 54. The outside of 75 the gauge is provided as usual with graduation marks to indicate the relative degree of compression of the spring 54.

It is to be noted that the nipple 3 and the gauge case 45 extend in the same direction, that is rearwardly, from the barrel 1 so as to afford a handle for my device that may be grasped by the hand of an operator. When so held, the plunger 7 may be conveniently depressed by any suitable means, as, 80 for example, by the thumb of the operator applied to a button 55 on the end of the plunger.

The following is a brief description of the 85 operation of my device.

Assuming that the nipple 3 is connected as by a flexible pipe, as it is in service, with a source of compressed air supply, the operator, when he wishes to use my device, applies the stud 33 to the ordinary filling nipple of a tire, with the effect of opening the valve of the filling nipple. Thereupon, the valve 20 being closed and the duct 6 open, as shown in Figure I, pressure from the tire is communicated through said duct against 100 the piston head 52, with the effect of compressing the spring 54. The degree of pressure is indicated by the movement of the gauge 48 by reference to the graduations 105 thereon.

If the degree of pressure indicated be lower than that desired, the operator, without further manipulation, simply depresses the plunger 7. Thereupon the packing ring 10 first closes the duct 6, and, afterwards, 110 the zone 17 of the valve actuating head 15, by engagement with the nose 21, opens the valve 20, with the effect of communicating air pressure through the ducts 28. A release of the plunger 7 effects immediate stoppage 115 of compressed air supply, and restores communication between the ducts 28 and the piston head 52 with like effect as that already described.

By repeated operations of the plunger 7, 120 if necessary, the tire pressure may be brought to the desired degree as indicated by the graduations on the gauge 48.

It is noted that whenever the valve 20 is opened by engagement between 17 and 21, 125 the duct 6 is closed by the packing ring 10, so that the device thereupon becomes, in effect, a simple air discharge outlet, controllable by manipulation of the plunger 7. It is because of this feature that I prefer to pro- 130

vide threads inside the ring 31, in order to accommodate the nozzle attachment 36, with the advantages of the uses derivable therefrom in the manner already specified.

5 What I claim is:

1. In a filler-vent, the combination with a barrel provided with a bore, and a pressure gauge on said barrel organized to form a handle for the device, of a pipe nipple on the same side of said barrel and substantially parallel with said gauge, an air control valve in said nipple having a nose extending into the bore of the barrel, a plunger reciprocatory in said bore, a valve actuating head actuated by said plunger into snub engagement with said nose for actuating the air control valve, and means for operating the plunger.

2. In a filler-vent, the combination with a barrel provided with a bore, and a pressure gauge, of a pipe nipple, an air control valve in said nipple having a nose extending into the bore of the barrel, a plunger reciprocatory in said bore, a valve actuating head ac-

tuated by said plunger into snub engagement with said nose for actuating the air control valve, and means operated by the plunger for controlling operative communication between the bore of the barrel and the gauge.

3. In a filler-vent, the combination with a barrel provided with a bore, and a pressure gauge on said barrel organized to form a handle for the device, of a pipe nipple, an air control valve in said nipple having a nose extending into the bore of the barrel, a plunger reciprocatory in said bore, a valve head provided with a conical zone actuated by said plunger into snub engagement with the said nose for actuating the air control valve, and means for operating the plunger.

In testimony whereof, I have hereunto set my hand in the presence of two subscribing witnesses.

ELIAS BERSON ROSE.
